Primary Examiner — W. A. Teddy Falloway

(74) Attorney, Agent, or Firm — Quickpatents, LLC;
Kevin Prince(57) **CLAIM**

I claim the ornamental design for a decorative bow with flowers, as shown and described.

DESCRIPTION

FIG. 1 is a perspective view of a decorative bow with flowers;

FIG. 2 is a top plan view of FIG. 1;

FIG. 3 is a front elevational view of FIG. 1;

FIG. 4 is a rear elevational view of FIG. 1;

FIG. 5 is a right-side elevational view of FIG. 1; and,
FIG. 6 is a left-side elevational view of FIG. 1.

It is understood that the bottom plan view of each embodiment forms no part of the claimed design.
